(57) CLAIM

The ornamental design for a raw cut edge swimsuit substantially as shown and described.

DESCRIPTION

FIG. 1 is a front view of a raw cut edge swimsuit including positioning strips on the inner side of the shoulder straps and inner side edges of the leg openings.

FIG. 2 is a front, inside-out view of the swimsuit showing positioning strips on the inner side of the shoulder straps, and the inner side edges of the leg openings and the arm openings.

FIG. 3 is a back view of the swimsuit including positioning strips.

FIG. 4 is a back, inside-out view of the swimsuit including positioning strips.

FIG. 5 is a front environmental view of the swimsuit on a wearer's body, with the raw cut edges of the swimsuit smoothly contacting the wearer's body.

FIG. 6 is a back environmental view of the swimsuit.

FIG. 7 is a left-side environmental view of the swimsuit; and,

FIG. 8 is a right-side environmental view of the swimsuit. The features shown in broken lines in the various Figures are for illustrating environmental structure and form no part of the claimed design.

More generally, the invention pertains to an ornamental design for a raw cut edge swimsuit.
